UNITED STATES PATENT OFFICE.

CHARLES D. SMITH, OF CHICAGO, ILLINOIS.

IMPROVEMENT IN FURNACES FOR STEAM-BOILERS.

Specification forming part of Letters Patent No. 119,056, dated September 19, 1871.

To all whom it may concern:

Be it known that I, CHARLES D. SMITH, of Chicago, in the county of Cook and State of Illinois, have invented a new and Improved Furnace for Steam-Boilers; and I do hereby declare the following to be a full, clear, and exact description thereof, which will enable others skilled in the art to which my invention appertains to make and use the same, reference being had to the accompanying drawing forming part of this specification, in which—

Figure 1 is a vertical cross-section of a boiler and furnace constructed in accordance with my invention, and Fig. 2 is a back or end view of the same.

Similar letters of reference indicate corresponding parts in the several figures of the drawing.

My invention has for its object to provide improved means for setting steam-boilers to secure a more perfect combustion of fuel, thereby securing a considerable reduction in the expense of heating the boilers; and to that end it consists in a furnace of stone or brick having a circular flue of brick or iron beneath the boiler constructed in the form of an inclined plane, its back or upper end being placed very near the boiler, causing the entire heat from the fire to radiate upon the boiler; it also consists in an oxidator placed beneath the flue, the current of air from which passes through the bottom of the

flue by means of a port formed therein, and also through the rear end of the furnace to the front of the boiler; it also consists in a port formed in the side of the boiler and passing into the flue.

In the accompanying drawing, A represents the boiler, which may be constructed in the ordinary manner. B is the flue, and C the bottom wall thereof. D represents the oxidator or lower flue, and E F the ports for supplying air to the flue. The air-passages being supplied with doors the amount of oxygen supplied to the flues can be controlled at pleasure.

By the use of my invention coal-slack, costing but one-third the price of coal, is found to work equally well and produce the same amount of heat, the gases arising therefrom being entirely consumed, a property impossible of accomplishment by the use of furnaces as ordinarily constructed.

Having thus described my invention, what I claim as new, and desire to secure by Letters Patent; is—

Flues B and D, in combination with sloping false bottom C and ports E and F, the whole constructed and arranged substantially as described, for the purpose specified.

CHAS. D. SMITH.
